UNITED STATES PATENT OFFICE.

CHRIST H. GANZEL, SR., OF BOYD, WISCONSIN.

MASONRY CHIMNEY AND SMOKE-FLEUE.

SPECIFICATION forming part of Letters Patent No. 610,396, dated September 6, 1898.

Application filed June 29, 1897. Serial No. 642,866. (No model.)

To all whom it may concern:

Be it known that I, CHRIST H. GANZEL, Sr., a citizen of the United States, residing at Boyd, in the county of Chippewa and State of Wisconsin, have invented certain new and useful Improvements in Masonry Chimneys and Smoke-Flues; and I do hereby declare the following to be a full, clear, and exact description of the invention, such as will enable others skilled in the art to which it appertains to make and use the same.

This invention relates to certain improvements in masonry construction, and more particularly to certain improvements in masonry chimneys and smoke-flues.

It is a well-known fact that a large percentage of the fires and conflagrations originating in dwellings and other houses start from and are caused by defective flues or chimneys and that such fires are of the most dangerous and destructive character because of their deceptive and concealed character and the fact that usually such fires smoulder unknown and unseen until they so increase in size and extent as to most suddenly and with swiftness burst through the walls and partitions and consume the dwelling with the greatest rapidity. One great cause for such fires is the defective construction of chimneys of brick or stone by reason of the spaces and crevices or cracks opening through the chimney or other flue from the interior smoke and flame passage thereof to the exterior of the chimney and the surrounding partitions and other woodwork, permitting the passage of flame and intense heat to the woodwork of the house. Such openings usually are found between the bricks or stone of which the chimney is constructed by reason of the improper placing of the mortar or because of the displacing of properly-placed mortar under the action of heat or cold or for other reasons or causes.

Usually masonry chimneys are lined with a coating of mortar or cement; but this usually peals and drops off under the action of the elements or is scraped off by the implements employed in cleaning the chimney, thereby opening the cracks or spaces between the bricks or stone.

The object of the invention is to provide certain improvements in constructions, com-

bination, and in details and arrangements of parts whereby an improved and highly-efficient and perfectly-safe masonry chimney is provided, overcoming all the dangers of fire hereinbefore mentioned.

The invention consists in certain novel features of construction and in combinations and in arrangements of parts, as hereinafter more fully explained and pointed out.

Referring to the accompanying drawings, Figure 1 is a vertical section taken centrally through an ordinary brick chimney, showing the same provided or combined with the flue or lining herein set forth, the lining being shown as when built up with the chimney. Fig. 2 is a detail perspective view of the two lower lining-sections as shown in Fig. 1. Fig. 3 is a cross-sectional view taken through the chimney and its improved flue or lining. Fig. 4 is an enlarged detail vertical section through the chimney and lining, showing the joint between two sections of the lining with their adjoining ends overlapping or telescoping.

In the drawings, *a* is a masonry chimney having the central flue and smoke flue *b* and the side or lateral openings *c* to receive the sleeves or thimbles communicating with the pipes or flues from the various stoves on different stories or in different rooms of the building. This chimney is here shown as constructed of bricks; but such a construction is illustrated merely as an example of a chimney of masonry, as the invention is as well adapted to chimneys constructed of stone or other material where openings or spaces are likely to form between the bodies or blocks cemented together to constitute the chimney. In the drawings several such spaces, openings, or crevices are shown between the bricks and are indicated by the reference-letter *d*.

As this invention is designed to render masonry chimneys fireproof and to reduce danger of fire therefrom to a minimum, it comprises such a chimney in combination with the peculiar improved interior lining of sheet metal, more fully specified hereinafter, which forms the interior smoke and heat flue and forms surrounding closed air-spaces and which can be built up with such a chimney or inserted in a chimney already constructed without requiring any change in the construction of the

masonry chimney and without directly securing the lining thereto. This lining is formed in a series of telescoping sections resting one in the other and fitting the chimney-flue without being secured thereto, except, possibly, by the sleeves or thimbles passing thereinto through the chimney, and with the bottom section resting on the floor at the bottom of the chimney-flue and the upper section ending at the top of the chimney, so that the lining extends throughout the length of the chimney-flue and completely incloses the flue and lines the walls thereof.

In Fig. 1 the lining *e* is placed in the chimney as the same is being built, and a bottom section *f* is provided to rest on the floor or base of the chimney. This bottom section *f* is formed with the horizontal outwardly-projecting bottom flanges *f'*, resting on said base and the bricks of the chimney and laid on said flanges, thereby rigidly and firmly securing the lining in place. The remaining sections *e'* making up the lining are then inserted as the chimney is built up, with the lower end of each section receiving the upper end of the one below. Each section is cut from sheet metal and is then bent to conform to the interior of the chimney, usually rectangular in cross-section, and the edges of the sheet metal forming each section are overlapped at one side of the section and are united near the lower end of the section by a rivet *e*' or other suitable means, preferably leaving the upper end of the section collapsible by not securing the overlapping ends together above said rivet. However, the lower or bottom section of the lining is usually riveted or otherwise secured both at the upper and lower ends of the section. With the sections thus formed their upper ends can be collapsed to the desired extent and inserted in the fixed lower ends of the sections above, and the spring of the sheet metal and friction at the telescoping ends and with the wall of the flue hold the lining in the proper place and position and firmly in place, and holes can be cut in the lining to receive the stovepipe sleeves or thimbles.

The lining can be easily and readily inserted in chimneys already built by first measuring the length and size of the chimney-flue and then properly forming and bending the sections of the size desired and telescoping them as they are inserted at the top of the chimney, the bottom section resting on the floor or base of the chimney, the holes in the lining for the stovepipe-thimbles having been previously properly located and cut in the proper sections. A chimney thus formed can be most easily cleaned from the top without endangering the safety of the chimney, and also there is no danger from the cracks and crevices opening in the chimney as the same settles, nor is the lining endangered or displaced by such settling, because the lining is not rigidly secured to the chimney, but merely rests loosely therein.

Although the flue or lining sections are usually made to generally conform to the interior shape of the chimney, yet said sections are made smaller in size than the interior of the chimney, so as to leave the air-space completely around the flue within the chimney. This is accomplished and the flue or lining is held in the proper position within the chimney by the strips or ribs *h* on the exterior of each lining-section and engaging the interior surface of the chimney and thereby centering the flue or lining and forming the air-space completely around the same and extending the full length of the chimney. The upper or top section of the flue or lining is flanged over the top of the chimney to close the upper end of such air-space within the chimney, and thus prevent sparks, &c., dropping down into the same.

The flue or lining is preferably rectangular in cross-section and is provided with a vertical longitudinal strip or rib at each side thereof, and these ribs are also preferably formed hollow, as shown, to constitute vertical air-spaces. Each section is formed with the side ribs, which are usually formed of strips of sheet-iron or other suitable metal bent U-shaped, with flanges riveted to the metal of the section, so that when the sections are joined together the various hollow ribs thereof will coincide or register and form the continuous ribs or strips of the entire lining or flue. Material advantages are attained by thus forming and providing the air spaces or passages around the flue or lining and within the chimney.

Having thus fully described my invention, what I claim as new, and desire to secure by Letters Patent of the United States, is—

1. A masonry chimney, in combination with a sheet-metal casing extending throughout the length thereof from the base of the chimney to the top thereof, said lining composed of telescoping sections in cross-section generally conforming to the interior of the chimney and having exterior means to engage the wall of the chimney and center the lining and form the surrounding air-space, the bottom or base section having the bottom lateral flanges *f'*, entering the masonry of the chimney at the base thereof and closing the lower end of said air-space, the top section having the top lateral flanges approximately at the top of the chimney and closing the top of said air-space, and the smoke-pipe *c*, entering the sheet metal lining through a section thereof, substantially as described.

2. A masonry chimney, in combination with a protective sheet-metal lining forming the smoke-flue and built up of short telescoping sections extending throughout the length of the chimney, the lining of a size to leave an air-space around the same, each section formed with several exterior hollow ribs engaging the inner surfaces of the chimney, the corresponding hollow ribs of the several sections abutting and registering at their ends as de-

scribed, the air-space and the ribs closed at the top of the chimney, whereby the construction of the chimney is not varied to receive the lining and the same can be built up with the chimney or inserted afterward.

3. A masonry chimney, in combination with a protective sheet-metal lining built up of sections forming the smoke-flue, and extending approximately throughout the length of the chimney with the surrounding air-space within the chimney, the bottom section having the lateral flanges closing the lower end of the air-space and the top section having the flanges resting on the top of the chimney and closing the top of the air-space, each section collapsible at one end only, as described, to fit in the end of the adjoining section, the section having the vertical exterior hollow abutting and registering ribs engaging the inner surfaces of the chimney.

4. A masonry chimney, in combination with a sheet-metal lining or flue therefor comprising

ing telescoping sections, each section bent from sheet metal with straight overlapping ends pivotally secured together near one end only as by a rivet e'' , so that the opposite end can collapse to enter the fixed end of the next section, substantially as described, whereby the lining can be built up with the chimney or inserted afterward, said lining extending approximately throughout the length of the chimney and in cross-section conforming to the interior thereof and centered to form the surrounding air-space closed at the top, thereby retaining the flame and smoke and preventing escape thereof through lateral crevices in the masonry of the chimney, as described.

In testimony whereof I affix my signature in presence of two witnesses.
